J. W. COLEMAN & A. GORDEN.

WIRE STRETCHER.

APPLICATION FILED MAY 10, 1913.

1,107,039.

Patented Aug. 11, 1914.

UNITED STATES PATENT OFFICE.

JOHN W. COLEMAN AND ALEXANDER GORDEN, OF SPOT, TENNESSEE.

WIRE-STRETCHER.

1,107,039.

Specification of Letters Patent. Patented Aug. 11, 1914.

Application filed May 10, 1913. Serial No. 766,739.

To all whom it may concern:

Be it known that we, JOHN W. COLEMAN and ALEXANDER GORDEN, citizens of the United States, residing at Spot, in the county of Hickman and State of Tennessee, have invented certain new and useful Improvements in Wire-Stretchers; and we do hereby declare the following to be a full, clear, and exact description of the invention, such as will enable others skilled in the art to which it appertains to make and use the same.

This invention relates to a new and improved device primarily intended for the purpose of stretching the wires of fences.

The principal object of the invention is to generally improve the construction and operation of the specified device for any of its possible uses.

Another object of the invention is to provide an improved fence wire stretcher which may be readily adapted to use as a wagon jack.

Another object of the invention is to provide an improved fence wire stretcher which may be readily adapted to use as a post puller.

With these objects in view, the invention consists in the improved construction, arrangement and combination of the parts of a fence wire stretcher adapted for use as a wagon jack or post puller, which will be fully described hereinafter and afterward specifically claimed.

In order that the construction and operation thereof may be readily comprehended, we will now proceed to fully describe our invention in connection with the accompanying drawings, which illustrate approved emendments thereof, and in which drawings,

Figure 1 represents in side elevation, a fence wire stretcher constructed in accordance with our invention, in position for use. Fig. 2 represents a transverse sectional view taken on the plane indicated by the broken line 2—2 of Fig. 1. Fig. 3 represents a sectional view taken on the plane indicated by the broken line 3—3 of Fig. 1. Fig. 4 represents the pawl lever and pawl, in inside elevation, detached from the machine; the handle end being broken away.

Like reference characters mark the same

parts wherever they occur in a plurality of the figures of the drawings.

Referring to the drawings in general 55 terms, 10 indicates a tree, post, or other fixed object to which our improved fence wire stretcher is to be attached, by chains 11, or in any other suitable manner, said chains connecting with the main body 12 of the 60 stretcher, upon which is mounted the slide 13, which in turn is connected by chains 14 with brackets 15 attached to a clamp 16, for grasping and holding the wires 17 of a fence. The main body 12 is provided with teeth 18 65 on one edge and similar teeth 19 on the opposite edge, and is longitudinally and centrally slotted at 20, which slot may or may not run through the clamp end of the main body but when it does run through, a plate 70 21 will be secured to the two branches of the body by bolts 22, or other suitable fastenings. The slide 13 is mounted, as before stated, on the main body 12 and consists of a plate on each side of the body, secured together by rivets 23 which pass through the slot 20 of the body, and rivets 24, which pass through the two plates of the slide outside of the edges of the body and far enough away therefrom not to interfere with or engage 75 the teeth 18.

On one side of the main body 12, between said body and one of the plates of the slide 13 and pivotally mounted on a rivet or bolt 25 which connects the two plates of the slide 85 20 and passing through the slot 20 of the main body, is a pawl lever 26. This pawl lever on its outer end carries a pivoted pawl 27, connected by a link 28 with a cross bar 29 pivotally mounted on a pin 30, which is slid- 90 able in the slot 31 in the pawl lever and is normally pressed inward toward the main body by a spring 32 coiled around a rod 33, and arranged to normally press said rod and the pin 30 toward the main body. The 95 spring 32 bears at one end against a lug 34, secured to the pawl lever, and at the other end against a nut or collar 35 on the rod 33, said rod being pivotally connected at 36 to a handle bar 37, pivoted at 38 to the pawl 100 lever. At the opposite end from the link 28, the cross bar 29 is connected by a link 39 with a pawl 40, pivotally connected to the pawl lever, the pawls 27 and 40 normally

held in yielding engagement with the teeth 18 and 19, respectively, of the body, by the yielding pressure of the cross bar 29 inward toward the main body, as will clearly appear.

5 The slide 13 being connected by the chain 14 with the clamp, when said slide is operated in the direction to the right, as illustrated in Fig. 1, said chain and clamp are both pulled to the right, carrying the wires 10 with them and thoroughly stretching them.

The slide is moved toward the right by oscillating the pawl lever 26, as follows: In their normal position the pawls 27, and 40, as before stated, yieldingly engage with the 15 teeth on the opposite sides of the body 12. When the handle end of the pawl lever is moved, say to the right, the point of engagement of the pawl 27 with the teeth 18 will become the fulcrum and the pawl lever will 20 oscillate on the pivot of that pawl, carrying the central pivot 25 of the pawl lever along in the slot 20 and sliding the pawl 40 over the teeth 19. When the end of this movement of the pawl lever to the right is 25 reached, by moving said lever to the left, the pawl 40 becomes the fulcrum and the lever will oscillate on the pivot of that pawl and slide the pawl 27 over the teeth 18 to take a new hold. When it is desired to remove the 30 pawls from contact with the teeth, the handle bar 37 is pressed toward the pawl lever which will draw outwardly on the rod 33, drawing the cross bar 29 outward and directly pulling the pawl 40 out of engagement with the teeth 19 and indirectly, 35 through the link 28, tilting the pawl 27 on its pivot, out of contact with the teeth 18. The slide can now be moved in either direction on the main body, this provision of free 40 movement being necessary in order to set the slide in the beginning of the operation, the slide and pawl lever being carried together in the sliding movement by reason of their connection by the rivet or bolt 25 which 45 passes through the slot 20, as before described. With the body 12 secured upon a post or tree 10 and the slide moving thereon in the manner described and carrying the clamp with it, the operation of stretching 50 wires will be obvious. It will be observed that the slide 13 projects to one side of the main body 12 and that the bar 21 at the end of the main body projects from both sides thereof. By detaching the chains from the 55 slide and from the main body, the body and attached slide may be set up vertically on the ground or a floor, resting on the plate 21 which would then become the base, when by inserting the projecting portion of the slide 60 under the axle of a vehicle, the described moving of the slide on the main body would raise the axle or other portion of the vehicle off the ground, the device in this case becoming a wagon jack, without altering any of 65 its working parts.

The manner in which the device may be utilized as a post puller will be identical with the manner of its use as a wagon jack with the single exception that chains similar to the chains 14 may be connected with the 70 slide to engage around the post.

While we have specifically described the construction, operation and arrangement of the various parts comprised in our invention, it will be obvious that changes and variations may be made therein within reasonable limits, without departing from the spirit and scope of the invention.

Having thus fully described our invention, what we claim and desire to secure by Letters Patent of the United States is:—

1. In a device of the character described, a main body toothed on its opposite edges and provided with a central longitudinal slot, a slide mounted on the body comprising plates on the sides thereof connected by bolts passing through said plates and the slot of the body, a pawl lever pivotally mounted on one of said connecting bolts, pawls pivotally mounted on said pawl lever on opposite sides of the body, means for holding said pawls yieldingly in contact with the series of teeth on the opposite sides of the body, said means comprising a cross bar longitudinally and pivotally movable with respect to the pawl lever, links connecting said pawls separately with said cross bar, and means for normally holding said cross bar toward the body.

2. In a device of the character described, a main body toothed on its opposite edges and provided with a central longitudinal slot, a slide mounted on the body comprising plates on the sides thereof connected by bolts passing through said plates and the slot of the body, a pawl lever pivotally mounted on one of said connecting bolts, pawls pivotally mounted on said pawl lever on opposite sides of the body, means for holding said pawls yieldingly in contact with the series of teeth on the opposite sides of the body, said means comprising a cross bar longitudinally and pivotally movable with respect to the pawl lever, links connecting said pawls separately with said cross bar, and means for normally holding said cross bar toward the body.

3. In a device of the character described, a main body toothed on its opposite edges, connected plates slidably mounted on the body to form a slide, a slotted pawl lever pivotally mounted on said slide, pawls pivoted on said lever on opposite sides of the body and adapted to contact with the respective series of teeth on the opposite sides of the body, a handle bar pivoted near one end of said pawl lever, a rod pivoted at one end to said handle bar, a pin on the opposite end

of said rod, extending through the slot in
said pawl lever, a cross bar pivotally mounted
on said pin, said pin being movable longitudinally
of said pawl lever, links separately
5 connecting said cross bar with said pawls,
and means to yieldingly press the cross bar
toward the body.

In testimony whereof we have signed our

names to this specification in the presence of
two subscribing witnesses.

JOHN W. COLEMAN.
ALEXANDER GORDEN.
